UNITED STATES PATENT OFFICE.

RICHARD C. HAGER, OF PHILADELPHIA, PENNSYLVANIA.

GLOBE-HOLDER.

1,255,163.

Specification of Letters Patent. Patented Feb. 5, 1918.

Application filed May 17, 1916. Serial No. 98,223.

To all whom it may concern:

Be it known that I, RICHARD C. HAGER, a citizen of the United States, and a resident of Philadelphia, in the county of Philadelphia and State of Pennsylvania, have invented certain new and useful Improvements in Globe-Holders, of which the following is a specification.

This invention relates to improvements in globe holders, and particularly to such as are intended to suspend a globe from or to support a globe on top of a lamp post.

The chief object of this invention is to provide a globe holder adapted to securely 15 and tightly clamp the rim of a globe without the danger of breaking or otherwise damaging it, the holder being further adapted to prevent the globe from being vibrated by the wind and to make a water tight joint 20 between the globe and its support.

With the above and related objects in view, my invention comprises the construction, combination and arrangement of parts hereinafter described, a practical application 25 whereof is illustrated in the accompanying drawing, and is embraced within the scope of the appended claims.

In the said drawing:—Figure 1 illustrates my improved holder in connection with a 30 globe suspended from a lamp post; Fig. 2 is an enlarged fragmentary section of Fig. 1; Fig. 3 is a perspective view of a section of the holder shown in Fig. 1; Fig. 4 is a plan view of the holder, and Fig. 5 is an 35 open view of the holder.

Referring more particularly to the drawing for a detail description of my invention, 40 6 represents a portion of a lamp post provided with an overhanging lamp 7, 8 represents an inclosing globe, 9 represents the globe holder, 10 represents an annular flange of the post surrounding the seat of the rim 11 of the globe.

The holder 9 is in the shape of a split 45 channelled ring joined by a hinge 12, one portion of the holder carrying a latch 13 and the other carrying a catch 14. Each half of the holder comprises a base 15, an outer upright flange 16 and an inner flared flange 50 17. The outer flange 16 is provided with bayonet slots 18 adapted to register with bolts 19 carried by the flange of the post.

The base of the holder is adapted to close

about the bight of the globe with its flange 17 about a packing 20 surrounding the flared 55 rim of the globe. When the holder is thus closed to carry the globe, it is adapted to receive the flange of the post between its own flanges with the bolts 19 projected through the bayonet slots of the flange 16 60 and to be clamped by the wing nuts 21.

The holder is also adapted to be suspended from the post by a chain 22 to gain access to the interior of globe.

Having thus described my invention, what 65 I claim as new and desire to protect by Letters Patent, is—

1. A globe holder comprising a channelled ring provided with bayonet slots on the outer side of the channel, the top of the 70 channel being narrower than its bottom, said ring consisting of two semicircular parts joined by a hinge at one end and provided with means for connecting and disconnecting the ends opposite the hinge. 75

2. The combination of a lamp post provided with an annular flange and a globe carrier provided with a channel for the post flange and with flanges on opposite sides of the post flange, the outer flange of the carrier being adapted to be joined with the post flange, said carrier consisting of two parts 80 hinged together at one end, said parts being adapted to close about the rim of the globe, and means for joining the parts to hold the 85 globe.

3. The combination of a lamp post provided with an annular flange and a globe provided with a rim adapted to be surrounded by the flange, a globe carrier consisting 90 of two sectors hinged together at one end and adapted to close about the rim of the globe, means for joining the sector at the opposite end to prevent the release of the globe, said carrier provided with a channel 95 for the post flange and with an exterior flange surrounding the post flange, and means for joining said flanges.

4. The combination of a lamp post provided with a seat surrounded by a flange and 100 a globe provided with a flaring rim for the seat of the post, a holder consisting of two sectors hinged together at one end and adapted to close about the rim of the globe and means for joining the sectors to hold 105 the globe, said holder provided with an in-

2
ner flange adapted to close about the rim of the globe and with an outer flange adapted to surround the flange of the post, said holder provided with a seat for the post 5 flange between said outer and inner flanges, and means for clamping the outer flange of the holder onto the post flange.

In testimony whereof I have signed this specification in the presence of two subscribing witnesses.

RICHARD C. HAGER.
